UNITED STATES PATENT OFFICE.

SAMUEL M. VAUCLAIN, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

JOINT FOR ARTICULATED LOCOMOTIVES.

1,099,076.

Specification of Letters Patent.

Patented June 2, 1914.

Application filed December 18, 1913. Serial No. 807,483.

To all whom it may concern:

Be it known that I, SAMUEL M. VAUCLAIN, a citizen of the United States, residing in Philadelphia, Pennsylvania, have invented 5 certain Improvements in Joints for Articulated Locomotives, of which the following is a specification.

My invention relates to certain improvements in locomotives of the "Mallet" type, 10 in which two frames are pivotally connected, each frame having its own motive power and a boiler extending over both frames.

The object of my invention is to improve the construction of the joint or coupling 15 which connects the two frames, so that the frames will have an independent vertical movement with respect to each other, as well as a lateral movement on the pivot pin.

In the accompanying drawings:—Figure 20 1, is a sectional plan view illustrating my invention located between the two frames of a locomotive of the "Mallet" type; Fig. 2, is a longitudinal sectional view on the line *a*—*a*, Fig. 1; Fig. 3, is a perspective view of the 25 coupling; Fig. 4, is a perspective view of the ball and sockets; Fig. 5, is a perspective view of the pivot pin; and Fig. 6, is a diagrammatic view illustrating in outline a "Mallet" locomotive to which my invention is applied.

Referring to the drawings, 1 is the rear frame of the locomotive and 2 is the forward frame.

3 is the boiler which extends over both 35 frames.

4, 4 are the driving wheels; one set of driving wheels being located under one frame and the other set being located under the other frame. These two frames are pivotally connected and, in some types of locomotives, the boiler is fixed to one frame and is arranged to swing over the other frame. Usually, the pivot consists of two parts with a vertical pivot pin connecting the parts so 40 as to allow the frames to accommodate themselves to the curve of the track.

It has been found in grades or uneven tracks that considerable strain is placed upon the parts of the coupling and, in some instances, these parts are liable to fracture, especially when one frame strikes the grade in advance of the other and, in order to allow the two frames to have independent vertical movement, as well as lateral movement, I

provide an improved coupling which I will now proceed to describe.

5 is a casting, in the present instance secured to the forward frame 2, and formed in this casting are the bearings 6 in which is secured a transverse pin 7. Mounted on this 60 pin is the coupling member 8 having two extensions 9 through which the pin 7 passes so that the said coupling is free to swing vertically on the pin 7.

In the outer end of the coupling member 65 8 is an opening 19 for the reception of a two-part socket 10 shaped to fit a ball 11, which is mounted on a vertical pin 12 extending through the bearings 13 in a casting 14 secured, in the present instance, to the rear frame 1. The casting 14 is formed to receive the socket end of the coupling 8 and has cheek pieces 18, which are spaced apart sufficiently to allow for a limited movement of the coupling member on the ball.

The pin 12 has a head 15 and is inserted in the bearings 13 and ball 11 from the underside and secured in position by a transverse bolt 16, which extends through lugs 17 on the underside of the casting 14.

It will be seen by the above construction that I am enabled to make a coupling or joint which connects the two frames of a "Mallet" locomotive, so that each frame will have an independent vertical movement and 85 will also have an independent lateral movement, and the ball will accommodate itself to any inequalities of the track so that neither frame will be subjected to torsional strains.

I claim:—

1. The combination in a locomotive, of two frames; a horizontal pivot pin carried by one frame; a coupling member pivotally mounted on said pin; and a universal coupling including a vertical pivot pin connecting the coupling member to the other frame.

2. The combination in a locomotive, of two frames; a transverse pivot pin on one frame; a vertical pivot pin on the other frame; a coupling mounted on the transverse pivot pin of one frame and having a socket; and a ball mounted in the socket and having an opening therein for the passage of the vertical pivot pin.

3. The combination in a "Mallet" locomotive, of two frames arranged one in advance

of the other, a boiler extending over both frames; a casting secured to the forward frame and having bearings; a transverse pivot pin mounted in the bearings; a coupling having two extensions forming bearings through which the pivot pin passes; a centrally located socket on the coupling; a ball mounted in the socket; a casting secured to the other frame and having bearings and cheek pieces; and a vertical pivot pin mounted in the bearings and extending

through the ball and socket, the portion of the coupling having the socket extending between the cheek pieces of the last mentioned frame.

15

In testimony whereof, I have signed my name to this specification, in the presence of two subscribing witnesses.

SAMUEL M. VAUCLAIN.
